UNITED STATES PATENT OFFICE.

THOMAS CORSCADEN, OF NEW BRITAIN, CONNECTICUT, ASSIGNOR TO THE STANLEY WORKS, OF SAME PLACE.

DESIGN FOR A SHELF-BRACKET.

SPECIFICATION forming part of Design No. 24,909, dated November 19, 1895.

Application filed December 13, 1894. Serial No. 531,726. Term of patent 14 years.

To all whom it may concern:

Be it known that I, THOMAS CORSCADEN, a citizen of the United States, residing at New Britain, in the county of Hartford and State of Connecticut, have invented and produced a new and original Design for a Shelf-Bracket, of which the following is a specification, reference being had to the accompanying drawing, forming part thereof, in which the only figure is a perspective view of a shelf-bracket showing my design.

A is the wall-plate and B the shelf-plate, the same having straight and parallel edges for the major portion of their length, as shown. At the outer end of each and surrounding the hole 1 there is a circular bead 2, which projects on the front of the wall-plate and under side of the shelf-plate, the reverse side of each bead being hollow, as shown at 3, on the upper side of the shelf-plate. The contour

of the end of said wall and shelf plates is concentric with said bead for about two-thirds of the circle described by said bead and then extends outwardly on straight lines 4 for a short distance, and then outwardly on curved lines 5 to meet the straight edges of said wall and shelf plates.

A brace C with curved parallel edges extends from the wall-plate to the shelf-plate, as shown. Upon the wall and shelf plates, along the middle line, is a bead 6, which extends continuously from one plate to the other, but stops a little short of the brace.

What I claim is—

The design for a shelf bracket substantially as herein shown and described.

THOMAS CORSCADEN.
